UNITED STATES PATENT OFFICE,

CHARLES L. HIGGINS, OF MONTREAL, CANADA, ASSIGNOR OF TWO-THIRDS TO CHESTER J. PIKE, OF MEDFORD, AND E. HUMPHREY PAINE, OF CAMBRIDGE, MASSACHUSETTS.

RUBBER BOOT OR SHOE.

SPECIFICATION forming part of Letters Patent No. 541,610, dated June 25, 1895.

Application filed April 13, 1895. Serial No. 545,562. (No model.)

To all whom it may concern:

Be it known that I, CHARLES L. HIGGINS, a subject of Victoria, Queen of Great Britain and Ireland, residing at Montreal, in the Dominion of Canada, have invented a new and useful Improvement in Rubber Boots or Shoes, of which the following is a full, clear, and exact description, reference being had to the accompanying drawings, forming a part of this specification, in explaining its nature.

The invention relates to a rubber boot or shoe especially adapted for the use of miners.

Such boots have been made of rubber with the exception of the heel and outsole which have been attached to the rubber insole of the boot or shoe in the ordinary way of attachment, namely, by nails or pegs driven through the sole into the rubber insole of the boot or shoe. This construction has been found to be objectionable in that the holes caused by the uniting nails or pegs often afforded channels or passages by which water or moisture found its way to the interior of the boot or shoe, and also because the boot or shoe so constructed was very stiff or inflexible, and where two leather soles were used, as was often the case, of course the disadvantages in this respect were increased.

In practicing my invention I take an insole and the usual upper part of the boot or shoe and treat them in the ordinary way for attachment to each other by vulcanization and I also unite to the insole and the turned in edge of the upper, by vulcanization, two or more layers of duck, canvas, or other suitable fabric preferably shaped to cover the entire under surface of the insole and to extend about the edge of the boot or shoe to form a section in the nature of a welt to which the leather sole is united; and in the further construction of the boot or shoe a leather sole is secured to this intermediate canvas or duck section by stitches passing through the edge of the leather sole and this welt or exposed edge of the canvas or duck section; and the sole is also further secured inside the line of sewing to the canvas or duck section by rubber cement. This provides a union between the leather sole and the remainder of the boot or shoe which does away with all holes ex-

tending to the insole to the interior of the boot or shoe, and it also forms a foundation for the reception of another leather or outsole of a nature to permit the said sole to be secured to the inner leather sole by nails or pegs, it being especially desirable in boots or shoes of this character that the outer sole shall be so secured; and I use for such purpose nails with large heads, such as hob nails, for the purpose of increasing the wear of the boot or shoe and also for the purpose of providing points or projections extending from the outsole to prevent slipping.

Referring to the drawings, Figure 1 is a view in longitudinal section of the boot. Fig. 65 2 is a view in cross-section representing one stage in its manufacture. Fig. 3 is a view representing upon the same section the second stage in its manufacture. Fig. 4 is a view upon the same section representing the final stage in its manufacture.

A represents the upper part of the boot or shoe. It is of the usual rubber fabric.

B is the insole which is also of rubber stock and to which the edge of the upper is united by vulcanization.

C represents the intermediate section of fibrous material preferably in the form of two or more layers of duck or canvas united together by a rubber compound and also to the insole and edge of the upper and thereto by vulcanization, this intermediate section C having an edge c in the nature of a welt but which may extend entirely around the heel end of the boot or shoe if desired. To this extension or welt c is then secured the leather sole D by stitches which extend through it near the edge and through the welt or extension outside the upper. d represents this line of attachment. The sole is further united to the intermediate section C by rubber cement. The leather outsole E is then attached to the remainder of the boot or shoe by nails or fastenings driven through it into the intermediate sole D but not through the rubber insole B, and for this purpose hob nails or any other wearing nails may be employed, and the heel F is attached to both leather soles in the usual way by nailing, the fastenings, however, not extending through the insole.

It will be seen that the rubber insole, the intermediate fibrous section C and the leather sole D form a very firm body or foundation for receiving and holding the fastenings for 5 securing the outsole and the heel which may not extend through the insole.

The advantages of the invention arise from the increased flexibility provided the soles and also from the waterproof character of the 10 construction, as all ways by which moisture can find access to the boot or shoe through the sole are done away with.

Having thus fully described my invention, I claim and desire to secure by Letters Patent of the United States—

1. A rubber boot or shoe having a rubber insole, the intermediate fibrous waterproof section united to the insole by vulcanization and having an edge extended beyond the 20 edge of the upper, a leather sole secured to this intermediate section by rubber cement

and by stitches passing through the exposed edge thereof and the edge of the sole, as and for the purposes described.

2. A rubber boot or shoe having a rubber insole, a rubber upper and a waterproof vulcanizable intermediate fibrous section united to each other by vulcanization, the said fibrous section having an exposed edge to act as a welt, a leather sole secured to said fibrous section 30 by rubber cement and by stitches passing through it near its edge and the edge of said fibrous section and an outsole and heel united to the intermediate leather sole D by fastenings which extend through it into said sole 35 but not through the insole, as and for the purposes described.

CHARLES L. HIGGINS.
